UNITED STATES PATENT OFFICE.

SEBASTIAN HINTON, OF WINNETKA, ILLINOIS, ASSIGNOR TO JUNGLEGYM, INC., OF CHICAGO, ILLINOIS, A CORPORATION OF ILLINOIS.

CLIMBING STRUCTURE.

Application filed October 1, 1920. Serial No. 414,030.

To all whom it may concern:

Be it known that I, SEBASTIAN HINTON, a citizen of the United States, and a resident of Winnetka, in the county of Cook and

5 State of Illinois, have invented certain new and useful Improvements in Climbing Structures, of which the following is a specification.

This invention relates to climbing apparatus, for children. It is an object of the invention to provide for playgrounds or the like, or for athletic establishments, in general, an apparatus wherein the manifest advantages of climbing as an exercise can be

10 freely utilized and made available, while the dangers incident to miscellaneous climbing, such as tree climbing or the like, can be minimized.

In a co-pending application, Serial No. 20 398,178, filed July 22, 1920, patented October 23, 1923, No. 1,471,465, I have disclosed an illustrative climbing apparatus comprising a structure made up of outline cubes or in other words, a reticulated structure so pro- 25 portioned and designed as to permit climbing in any direction. The structure there shown was fabricated out of cut-to-length oppositely threaded pipe and has been em- ployed with great success.

30 In the drawings, which represent an illustrative embodiment of the invention:

Fig. 1 is an elevation of a climbing structure, made in accordance with the invention,

Fig. 2 is an enlarged perspective view of 35 one corner thereof,

Fig. 3 is a broken out elevation, showing a compression member,

Fig. 4 is a perspective view, separated out, showing one of the central couplings and 40 associated climbing elements, and

Fig. 5 is a cross sectional view showing certain details of the coupling construction.

The structure as a whole is a reticulated rectangular structure which may be made 45 of any desired size, provided its proportions are practical. It comprises a series of vertical elements referred to generally by reference character 1, and two series of horizontal elements referred to generally by reference characters 2 and 3, Fig. 2, the series of elements 2 being preferably at right angles to series 3.

50 The structure is so designed that a boy, for instance, of eight years old, may make 55 a diagonal climb from one horizontal climb-

ing element above, in the next adjacent vertical plane; the climb being facilitated by grasping the horizontal climbing element above that to which the climb is made.

In an illustrative form of the apparatus, 60 which has been in actual use, the horizontal elements are spaced two feet apart, horizontally and vertically. I have found, however, that children seem to like to climb through the structure to some particular point and 65 there swing head downward by the knees, calling back and forth to each other, a trick which can be explained of course only by the monkey instinct.

The present illustrative form of the structure is designed to afford greater opportunities for this, as well as to permit lateral progress through the structure, somewhat more easily than that possible with the structure in which the cubes are two feet 70 on a side. Thus, referring to Fig. 2, I make the horizontal bars 2 and 3, comprising the bars in each vertical plane, three feet apart, and I stagger these bars in adjacent parallel vertical planes so that the distance 75 between parallel adjacent bars, in adjacent vertical planes will be a foot and one half in a vertical direction. Thus the vertical distance between the outside bar 3' and the bar 3, (Fig. 2) is one and one half 80 feet and the distance between the bars 2 and the adjacent bars 2', (Fig. 2) will also be a foot and one half in a vertical direction, this relationship being preferably persisted in throughout the entire structure no matter 85 what its size, and being varied only at the top and bottom where additional bars such as 2² are inserted to make the structure level.

In this form of apparatus, an eight year old boy, being approximately four feet high, 90 can easily duck through the three feet space between superposed horizontal bars, while at the same time he can readily make the diagonal climb previously referred to. He can also comfortably swing by his knees from 95 any of the horizontal bars, without hitting his head on the horizontal bar immediately below.

In the structure herein disclosed, I make the horizontal distance, or length of the 100 horizontal climbing elements 2 and 3, two feet. Thus the horizontal unit in the illustrative structure herein disclosed is two feet, the vertical unit is three feet, and the climbing unit, is a diagonal climb, on a 110

diagonal whose base is two feet and whose vertical side is one and one half feet,—in other words the climb between the lower element 3' (Fig. 2), and the next element 3 5 above it.

I shall now more specifically describe the structure shown in the drawings. For the verticals 1, I preferably employ throughout, 10 oppositely threaded pipe sections. By examination of the structure shown in Fig. 2, (which will reveal that structure better than a description), it will be seen that every alternate vertical support will be made in three foot lengths with couplings at the top and 15 bottom, as shown at 1, 1' in Fig. 2. The couplings used with the verticals 1, 1' will be six way couplings 4, in the interior of the structure, and four way angle couplings on the corners as indicated at 4' and four way 20 plain crosses at the top and bottom as indicated by 4², all couplings being oppositely threaded in the vertical run.

Of course six way couplings could be used throughout, if desired; that is in the place 25 of the couplings 4' and 4² and all the surface couplings correspondingly modified, to permit additions to the structure after it is first erected.

The other series of vertical members will 30 comprise pipe lengths 12 one and one half feet in length or rather of such a length that two thereof and the intervening coupling 5 will make up a length equal to the length of the three foot couplings 1'. With this 35 series of verticals, the couplings will be plain crosses such as shown at 5, throughout the structure and other plain crosses or T's such as shown at 5' on the surface, and four way angle crosses, such as shown at 5² at the 40 corners.

I will now describe the couplings employed. The outside couplings, i. e. those couplings upon the four vertical sides and the top of the structure, will be oppositely 45 threaded in each run and the associated horizontal bars 2', 2², and 3', 3², Fig. 2, will be oppositely threaded steel pipe to correspond. Thus the entire outer wall or skin 50 of the structure will be fabricated out of oppositely threaded pipe and couplings to match.

The interior couplings such as 4, whether 55 six way couplings, as there shown, or four way couplings 5, will be cast to correspond to the shape shown in Fig. 4, and oppositely threaded in the vertical run only as shown at 6.

The climbing elements in the illustrative 60 embodiment of the invention herein disclosed are made of pipe. The interior couplings are therefore suitably made as shown in Figs. 4 and 5, to present threaded sockets 6 in the vertical run, and smooth sockets 7 for the horizontal run. Each horizontal run is provided with a shoulder 8.

One end of each horizontal run is provided with a cast lug 9, and one end of each plain climbing element 2 or 3 is milled as at 10 to engage said lug. This is to prevent the bars from turning.

70

The assembly of a construction of the type shown will be exceedingly simple. Thus, for instance, two adjacent outer walls can be erected of oppositely threaded pipe. After this the roof or ceiling may be put on. 75 The verticals may be put together on the ground and suspended in the ceiling, certain thereof extending into holes in the ground, in which they may be blocked up on a brick or stone to support the ceiling. When all the verticals are in place, the climbing elements 2 and 3 can be inserted by springing the verticals apart enough at each coupling to permit this. There the two remaining sides can be put on, of oppositely threaded 80 pipe. After this by going over the outer layer, or skin of the structure, comprising the four walls and the top, with a pipe wrench, this skin can be shrunk to put the interior under very heavy compression. The 85 compression so produced will cause the climbing bars 3 and 2 to abut so firmly against the shoulders 8, in their sockets, that they can never be pulled out by a child, and they will brace the verticals from all sides. 90

However, if it be found to be desirable to add additional ties toward the center of each vertical wall this may be done in the manner shown in Fig. 3, wherein a heavy tie wire 11 is employed, which passes through the structure inside a succession of aligned pipes 2 or 3 and is attached at one end to the cap 12, at the other to the bolt 13, passing through cap 14, and tightened by nut 15. The surface coupling, in association with the tie wire, may either have an extra run as shown or be merely drilled to permit the tie wire to pass through to the outside of the structure.

100

As many of these ties can be placed across the structure as desired, though it is not believed that any will be necessary, except possibly in a very large structure. After the structure has been thus tightened up, the holes in which the verticals rest can be 105 filled with concrete. Of course other methods of erection may be employed.

110

I make considerable point of the great strength of the structure, as this is important. Thus most persons have seen a monkey in a zoo, seize the bars of his cage with hands and feet and throw his body violently back and forth, other monkeys following suit. Children in the structure I have erected do the same thing, apparently unconscious of any imitation of monkeys. It can be appreciated that with twenty-five or thirty heavy boys doing this, the strains on the structure are very great. In the structure herein disclosed the walls and top 120

115

125

130

are extremely strong, being made of oppositely threaded fabricated pipe turned up tight. The verticals are of pipe rigidly secured at their tops in the top or ceiling 5 of the structure and many of them sunk in concrete at their bases. All of them are braced either every three feet or every foot and a half by the climbing elements 2, 3, which impinge against the verticals or four 10 sides under heavy pressure. The structure is then made strong enough to stand severe strains which for safety's sake is extremely desirable.

Crossed ropes 14 can be employed at the 15 bottom of the structure, and as much as desired upward from, say, about the level of six feet, including the top, can be covered with ordinary fence wire, if desired, to prevent children falling off the outside of the 20 structure. This has been omitted from the drawings as it would confuse them. It is not believed that either of these precautions will be necessary, as a child falling in the structure will have so many opportunities 25 to catch a bar or vertical, that it is almost impossible that he will fall through it to the ground.

The structure herein shown is extremely efficient for supervised athletic work. Thus 30 classes of children can be put into one of these structures and made to take almost any conceivable exercise. The structure is compact and may be employed in the most limited playground. In order to further improve the efficiency with a class of children, I have used on the level of three and six 35 feet above the ground an alternately spaced five way coupling instead of four, or six way instead of five on the outside of the 40 structure. In the extra threaded socket thus provided, the bars 16 are tightly screwed, and are connected by a rail 17, shown in cross section. Additional diagonal braces 45 may of course be employed to support this bar 16.

These bars form chinning bars on which an entire class of children can take chinning exercises, as a part of various tests or exercises customarily used in supervised 50 athletic work. It has been a problem in this field heretofore, to find adequate means whereby a large number of children can all chin themselves at once in competition.

Having now described my invention, I 55 claim:

1. In a playground apparatus, a reticulated climbing structure, comprising in combination an outer layer adapted to be shrunk, an inner body comprising vertical 60 supports and horizontal climbing bars, associated with said vertical supports by slip joints, whereby said inner body may be put into compression by shrinking said outer layer to prevent disengagement at said slip 65 joints.

2. A climbing structure for playgrounds, comprising supports, climbing bars, arranged thereon and offset from each other laterally adjacent climbing bars being in different vertical planes, and spaced to permit a diagonal climb by an average child of predetermined age from one climbing bar to another laterally offset therefrom. 70

3. A climbing structure for playgrounds or the like, comprising supports, climbing 75 bars, arranged thereon and offset from each other laterally adjacent climbing bars being in different vertical planes, and spaced to permit a diagonal climb by an average child of predetermined age from one climbing bar to another laterally offset therefrom, 80 said climbing bars extending in two directions in two series of parallel bars.

4. A climbing structure for playgrounds, for athletic grounds or the like, comprising 85 supports, climbing bars, arranged thereon and offset from each other, laterally adjacent climbing bars being in different vertical planes, and spaced to permit a diagonal climb from one climbing bar to another laterally offset therefrom, 90 said climbing bars being arranged to permit a diagonal climb from one bar to an adjacent bar laterally offset therefrom, the next bar above the bar to which the climb is made being within reach of the hands to facilitate the climb. 95

5. A climbing structure for athletic grounds or the like, comprising a plurality of vertical supports, a plurality of horizontal climbing bars secured thereto, said 100 climbing bars being arranged in two non-parallel series, a plurality of the bars in each series being parallel to each other, said bars being so arranged that adjacent bars in horizontal directions are on different 105 planes.

6. A climbing structure for athletic grounds or the like, comprising a plurality of vertical supports, a plurality of horizontal climbing bars secured thereto, said 110 climbing bars being arranged in two non-parallel series, a plurality of the bars in each series being parallel to each other, said bars being so arranged that adjacent bars in horizontal directions are on different 115 planes, the bars being approximately two feet in length and three feet apart vertically.

7. A climbing structure for athletic grounds or the like, comprising a plurality of vertical supports, a plurality of horizontal climbing bars, secured thereto, said climbing bars being arranged in two non-parallel series, a plurality of the bars in each series being parallel to each other, said 120 bars being so arranged that adjacent bars in horizontal directions are on different 125 planes, and so spaced that a diagonal climb from one bar to the adjacent bar may be made by an average child of predetermined 130

- age, the bar above the one to which the climb is made being so spaced therefrom that it may be conveniently reached by said child during the climb.
- 6 8. A rectangular climbing structure comprising a series of vertical supports, horizontal bars arranged at right angles to each other and secured to said supports, said horizontal bars being arranged in vertical planes and the bars in each vertical plane being offset vertically from the bars in adjacent vertical planes.
- 10 9. A rectangular climbing structure for playgrounds comprising a series of vertical supports, horizontal bars arranged at right angles to each other and secured to said supports, said horizontal bars being arranged in vertical planes and the bars in each vertical plane being offset vertically from the bars in adjacent vertical planes.
- 15 10. A climbing structure for playgrounds or the like comprising a series of vertical supports, horizontal bars arranged at right angles to each other and secured to said supports, said horizontal bars being arranged in vertical planes and the bars in each vertical plane being offset vertically from the bars in adjacent vertical planes, all so constructed proportioned and arranged as to permit climbing in any direction through the structure, by an average child of predetermined age.
- 20 11. A climbing structure for playgrounds or the like comprising, in combination, a plurality of vertical supports, couplings arranged in said supports, horizontal climbing bars fitted at their ends to said couplings by slip joints and arranged to cross each other to form a cellular structure, and means for holding the structure together.
- 25 12. A climbing structure for playgrounds or the like comprising, in combination, a plurality of vertical supports, couplings arranged in said supports, horizontal climbing bars fitted at their ends to said couplings and extending in a plurality of directions to make a cellular structure, the horizontal bars in the interior of the structure being fitted to the couplings by slip joints, those on the surface being fitted to the couplings by positive joints.
- 30 13. A climbing structure for playgrounds or the like comprising, in combination, a plurality of vertical supports, couplings arranged in said supports, horizontal climbing bars fitted at their ends to said couplings, said vertical and horizontal elements forming a cellular structure, the horizontal bars in the interior of the structure being fitted to the couplings by slip joints, those on the surface being fitted to the couplings by threaded joints.
- 35 14. A climbing structure for playgrounds or the like made of lengths of pipe and pipe couplings and comprising a three dimensional structure made up of a series of vertical supports, pipe lengths fitted horizontally between said couplings by slip couplings between said supports in the interior of the structure and by threaded positive couplings on the surface of the structure.
- 40 15. A climbing structure for playgrounds or the like made of lengths of pipe and pipe couplings and comprising a series of vertical supports, pipe lengths fitted horizontally between said supports in the interior of the structure and by threaded positive couplings on the surface of the structure, and tension means to keep the structure from spreading, extending through certain of said pipe lengths.
- 45 16. A climbing structure for athletic grounds or the like comprising a cellular structure made up of cells bounded by climbing elements, to permit climbing progress by an average child of predetermined age through the structure in three dimensions electively, said climbing elements being connected together by slip joints, and an outer layer or skin adapted to be shrunk on the structure to put the interior thereof in compression.
- 50 17. A climbing structure for playgrounds comprising a cellular climbing frame, adapted to permit elective climbing in three dimensions by an average child of predetermined age from points in its interior, said structure being fabricated out of pipe, with slip joints in its interior, and an exterior surface or skin comprising oppositely threaded horizontal pipe sections verticals and corresponding couplings whereby the skin can be shrunk on to put the interior into compression.
- 55 18. A climbing structure for playgrounds, adapted to permit elective climbing in three dimensions from points in its interior by an average child of predetermined age, said structure being fabricated out of pipe and having lugs and recesses co-operating in the horizontal pipe sections to prevent the same from turning, and means to hold the structure together and in interior compression.
- 60 In witness whereof, I hereunto subscribe my name this 22d day of September, A. D., 1920.
